UNITED STATES PATENT OFFICE.

OTTO P. SCHUMAN, OF PHILADELPHIA, PENNSYLVANIA, ASSIGNOR TO THE RAPID CALCULATOR COMPANY, A PARTNERSHIP COMPOSED OF RICHARD C. ROSENTHAL AND OTTO P. SCHUMAN, BOTH OF PHILADELPHIA, PENNSYLVANIA.

CALCULATING MACHINE.

Application filed November 8, 1919. Serial No. 336,595.

To all whom it may concern:

Be it known that I, OTTO P. SCHUMAN, a citizen of the United States, residing in Philadelphia, Pennsylvania, have invented

- 5 Improvements in Calculating Machines, of which the following is a specification.
- This invention relates to improvements in calculating machines, and more particularly to that class of machines comprising a movable carriage bearing the registering elements of the mechanism, which carriage is adapted to be shifted laterally of the setting mechanism to bring the registering elements into positions successively engaging the various elements of the setting mechanism.

10 The object of my invention is to provide means whereby the carriage may be shifted successively and without use of undue care and effort to the exact positions in which the fixed elements of the setting mechanism will engage the different elements of the registering mechanism borne by the carriage.

15 In the attached drawings:-

Fig. 1 is a view in perspective of the entire 20 machine;

Fig. 2 is a plan view of the base of the machine with the carriage removed and with the carriage body indicated in broken lines;

25 Fig. 3 is a front elevation of the base, the body of the carriage being indicated in broken lines;

Fig. 4 is a vertical section of the base taken on the line *c-c*, Fig. 5.

30 Fig. 5 is a horizontal section of the base 35 taken on the line *a-a*, Fig. 7, showing details of the shifting mechanism;

Fig. 6 is a vertical section of the base taken on the line *b-b*, Fig. 7.

35 Fig. 7 is a vertical section of the base 40 taken on the line *c-c*, Fig. 5.

Fig. 8 is a detached perspective view showing the details of the construction of the retaining fork.

With reference to the drawings, the calculator comprises a base or pedestal 1, a main housing 2, secured to the base, and a carriage 3, mounted upon the base and adapted to slide longitudinally thereon. The carriage 3 comprises a body 3^a, and housing 3^b, upon

45 and within which is mounted the mechanism which registers the calculated results, this registering mechanism being actuated by

setting mechanism mounted on the housing 2. The elements of the two mechanisms are made to coincide by the interaction with a series of slots 5, in the base, of a spur 4^a upon a shifting lever 4, carried by the carriage. The lever 4 is pivotally mounted, at 4^b, upon the carriage body, and pressure exerted downwardly upon the outer extremity 4^c, 55 raises the spur away from engagement with the slots, and permits the carriage to be shifted longitudinally either to right or left.

This invention relates to improvements in calculating machines, and more particularly to that class of machines comprising a movable carriage bearing the registering elements of the mechanism, which carriage is adapted to be shifted laterally of the setting mechanism to bring the registering elements into positions successively engaging the various elements of the setting mechanism.

It becomes necessary in manipulating the machine for certain purposes, to bring the elements of the registering mechanism into successive engagement with certain of the elements of the setting mechanism. This entails shifting the carriage one step at a time to the right or left as the case may be, and 60 it has been found extremely difficult to move the carriage swiftly and at the same time with the precision necessary for engaging the spur 4^a accurately in the successive slots. Much time is consequently lost in this operation.

70 I have discovered means whereby the carriage may be shifted accurately and with facility from one position to another without exercise of undue care and without distraction of the operator's attention from the particular computation in hand.

75 Mounted within the base 1 is a plate 6, said plate having an apertured lug 6^a at each side of the nether surface thereof through which passes a rod 7, secured at each end to the said base, the plate 6 being free to oscillate upon the rod 7, and also to reciprocate longitudinally thereon, both within limits which will shortly be described. Secured to 80 the plate 6 upon the upper surface thereof is a bar 8, which extends into an elongated aperture 1^a in the upper face of the base 1, and which is slotted to correspond with the series of slots 5 in the base, the said bar 8 85 lying adjacent the slotted portion of the base in such position that the slots 8^a in the bar normally form a continuation in a lower plane of the slots 5 in the base. The relative positions of the two sets of slots are 90 most clearly illustrated in the plan view of Fig. 2 and in the vertical section of Fig. 7.

95 Mounted within the casing 1 and lying beneath the front portion of the plate 6,

is a plate 9, said latter plate having a lug 9^a at each side thereof extending backwardly, said lugs being apertured to receive the rod 7, which extends therethrough. An extension 9^b of the plate 9, extends through a slot 1^c in front of the base, and a stirrup shaped operating handle 9^c is secured to the said extension 9^b upon the outside of the base. The extension 9^b passing through the slot 1^c, prevents oscillation of the plate 9 upon the rod 7, but is sufficiently narrow in proportion to the length of the extension, 1^b, to permit longitudinal movement of the said slot therein, and in this manner the plate is adapted to reciprocatory movement upon the rod 7.

Upon the under side of the plate 6 is a cam 10, which extends downwardly into a slot 9^d, in the plate 9, while an arm 6^b extends rearwardly from the said plate 6, and normally lies between the forks 11^a of the retainer 11, pivotally mounted upon a pin 12, secured to the base 1. The normal position of the arm 6^b is retained by a stirrup lever 13 pivotally mounted at its extremities upon the pin 12 and passing underneath the arm 6^b. Springs 13^a, suspended from a bracket 14 mounted upon the base 1, pass through apertures 1^e in the said base and attach to said lever at each side thereof, whereby the lever is made to exert a pressure upwardly upon the underside of the arm 6^b, to hold the latter in the said normal position. A spring 15, suspended from a bracket 16, mounted upon the base 1, passes through an aperture 1^f in the said base and attaches to the retainer 11. The spring 15 while permitting oscillatory movement of the retainer upon the pin 12, exerts an upward pull upon the retainer and tends to hold the same in normal position, wherein the forks 11^a lie upon either side of the arm 6^b upon the plate 6. The normal position of the retainer 11, and of the arm 6^b, is most clearly shown in Fig. 7, and it is clear that in this position any reciprocatory movement of the plate 6 longitudinally upon the rod 7, is prevented.

Extending downwardly from the under side of the plate 6, are two pins 6^c, said pins being adapted to engage the inner edges of two levers 17, pivotally supported within the base 1. A spring 17^a extends between the two levers 17, and tends to hold them together, while pins 17^b, carried by the base 1, hold the levers in the normal, substantially parallel, position shown in Fig. 5.

Let us now suppose that the plate 9, is moved laterally to the limit of its travel and allowed to return to its normal position. The first effect of the lateral movement of the plate 9 will be to rotate the plate 6 upon the rod 7, this rotation being caused by the interaction of the plate 9 with the cam 10, and the plate 6 being held from lateral

movement by the arm 6^b and the retainer 11. The continued rotation of the plate 6 finally results in the elevation, through contact with the slotted bar 8, of the rear portion of the lever 4, and the raising of the spur 4^a from the slot 5, which it occupies at the time, the said spur 4^a at the same time occupying one of the slots 8^a in the bar 8. As the spur 4^a clears the slot 5, the arm 6^b passes clear of the forks 11^a of the retainer 11, and the plate 6 is thereby permitted to move laterally along the rod 7. The relative positions of the parts as just described, are shown in Fig. 4. The lateral movement of the plate 6, which now occurs, is in the present instance obtained by the interaction of the plate 9 and cam 10, the oscillation of the plate 6 being stopped by contact with the top of the base before the cam has entirely left the aperture 9^d, and the cam thus remaining continuously in operative engagement with the plate 9. Should, however, the oscillation of the plate 6 be great enough to cause the cam 10 to ride completely out of the aperture, the transmission of the translatory movement may be obtained by interaction of one of the lugs 9^a located intermediate the lugs 6^a upon the rod 7, and the sleeves 18, also carried by the rod 7, and interposed between the said lug 9^a and the lugs 6^a. The sleeves 18 are of such length as to permit movement of plate 9 independent of the plate 6 of sufficient extent to enable the said plate 9, by acting upon the cam 10 to rotate the plate 6 until the arm 6^b is clear of the forks 11^a, but immediately following the clearance of the said arm, the lug 9^a through the intermediate sleeve 18 will bear against one or other of the lugs 6^a, and cause the plate 6 to move laterally with the plate 9, the arm 6^b passing underneath one or other of the forks 11^a, depending upon the direction of the motion. Whether to the right or to the left, this lateral movement of the plate 6 is always just sufficient to move the lever 4, and consequently the carriage to which the lever is attached, until the spur 4^a, lies directly over the slot 5, adjacent to the slot previously occupied, and just vacated thereby. Thus movement of the plate 9 either to the right or left extreme position thereof will effect the shifting of the carriage one step or position.

When the plate 6 has traveled the extreme end of its path, the arm 6^b, has passed completely under the fork 11^a, and lies clear of the outer edge thereof. At this point the stirrup lever 13 comes into play, for as soon as the plate 9 is released the said lever 13 forces the arm 6^b upwardly along the outer side surface of one of the retainer forks 11^a, and at the same time this rotation of the plate 6 causes the depression of the slotted bar 8, and the deposit thereby of the

spur 4^a of the lever 4 in the slot 5, above which it was moved by the lateral motion of the plate 6 as previously described.

As the arm 6^b approaches its normal elevation, the spring 17^a comes into play and through the medium of one or other of the levers 17, and of the corresponding pin 6^c, upon the plate 6, tends to return the said plate 6 to the normal intermediate position shown in Fig. 5. The outer sides of the forks 11^a of the retainer 11, curve upwardly, as clearly shown in Fig. 8, and there develops between these curved sides and the arm 6^b a cam action which depresses the retainer 11 against the tension of the spring 15, which supports it, and permits the plate to return to the said normal position wherein in the arm 6^b lies between the forks 11^a, the spring 15 returning the retainer 11 to normal elevated position as soon as the arm 6^b has passed beneath the fork.

From the foregoing description it will be seen that the mere manipulation of the plate 9 to the full extent of its travel to right or left, transmits to the carriage through the plate 6, an exact and positive movement in the chosen direction which advances the said carriage accurately from one position to the next succeeding position, and that this shifting of the carriage is accomplished with the least possible delay and distraction of the operator's attention.

For the purposes of this application, "reciprocation" and "oscillation" are to be understood as defining two separate and distinct kinds of motion, "oscillation" requiring a relatively fixed pivot passing through the body and about which the body moves, and "reciprocation" defining a back and forth motion in which there occurs translation of all parts of the body in the same general direction at the same time.

I claim:

1. In a calculating machine the combination with a base structure, of a carriage movably mounted and having a plurality of locked positions on the base structure, and manually operated mechanism for shifting the carriage on the base including an actuating member relatively fixed with respect to the carriage and adapted by movement in a single straight line to shift the carriage from one locked position to another in each direction.

2. In a calculating machine the combination with a base structure, of a carriage movably mounted and having a plurality of locked positions on the base structure, and manually operated mechanism for shifting the carriage on the base including an actuating member mounted in the base adapted by movement in a single straight line to shift the carriage progressively from one locked position to another in each direction.

3. In a calculating machine the combina-

tion with a base structure, of a carriage movably mounted and having a plurality of locked positions on the base structure, manually operated means for shifting the carriage on the base including a relatively fixed actuating member adapted by movement in a single straight line parallel to the direction of movement of the carriage to shift the latter from one locked position to another, and transmission elements operatively connecting the actuating member with the carriage.

4. In a calculating machine the combination with a movable carriage, of a carriage engaging member normally disengaged from the carriage and having two distinct movements respectively for engaging and shifting the carriage, and an actuating member operatively associated with said engaging member and adapted by simple movement in a single straight line to give the engaging member successively the movements first to engage and then to shift the carriage.

5. In a calculating machine, the combination with a movable carriage, of a carriage engaging member normally removed from the carriage, and mechanism for communicating to said member one motion for engaging and disengaging said carriage, and another motion for shifting said carriage.

6. In a calculating machine, the combination with a movable carriage, of a carriage engaging member normally removed from the carriage, and mechanism for communicating to said member vertical motion for engaging and disengaging said carriage, and horizontal motion for shifting said carriage.

7. In a calculating machine, the combination with a movable carriage, of a carriage-engaging member normally removed from the carriage, and manually operated mechanism for bringing said member into engagement with the carriage and for moving said member to shift the carriage.

8. In a calculating machine, the combination with a supporting frame, of a carriage mounted and movable laterally upon said frame, manually operated mechanism for shifting said carriage, and a member mounted on the frame and movable laterally of said carriage for actuating said mechanism.

9. In a calculating machine, the combination with a supporting structure, of a carriage mounted and movable thereon, a shaft mounted in said structure, an element pivotally mounted upon and movable longitudinally of said shaft, and means for oscillating said element upon the shaft to bring it into engagement with the carriage and for shifting said element longitudinally of the shaft to move the carriage on the said structure.

10. In a calculating machine, the combination with a movable carriage, of mechanism for shifting said carriage, said mechanism comprising a reciprocatory actuating

- 4
- member, a transmitting member both reciprocatory and oscillatory, and means whereby reciprocation of said actuating member effects alternate oscillation and translation of 5 said transmitting member.
11. In a calculating machine, the combination with a movable carriage, of mechanism for shifting said carriage, said mechanism comprising a reciprocatory actuating 10 member, an intermediate member both reciprocatory and oscillatory, a carriage engaging member carried by said intermediate member, and means whereby reciprocation of said actuating member effects movement 15 of said engaging member in a substantially rectangular path.
12. In a calculating machine, the combination with a movable carriage, of mechanism for shifting said carriage, said mechanism comprising a reciprocatory actuating 20 member, an intermediate member both reciprocatory and oscillatory, a cam upon said intermediate member in engagement with said actuating member, means for transmitting 25 the translatory motion of the actuating member to the intermediate member, and a retainer normally preventing translation of said intermediate member while leaving said member free to oscillate, said 30 retainer being adapted to release the intermediate member after the latter has been oscillated.
13. In a calculating machine, the combination with a movable carriage, of mechanism 35 for moving said carriage, said mechanism comprising a reciprocatory actuating member, an intermediate member both reciprocatory and oscillatory, a carriage engaging member carried by said intermediate member, a cam upon said intermediate member extending through an aperture in said 40 actuating member, means whereby translation of the actuating member effects translation of the intermediate member, a spring 45 opposing oscillation of the intermediate member, a second spring opposing translation of said intermediate member, and a retainer preventing translation of the intermediate member until the said member has 50 first been oscillated.
14. In a calculating machine, a base portion, a carriage movably mounted thereon, an actuating member slideable in said base portion, a shaft mounted in said base portion, an intermediate member movable upon 55 said shaft and having carriage-engaging means, a cam carried by said intermediate member adapted to be engaged by said actuating member whereby said intermediate member is rocked upon the shaft to bring 60 the carriage-engaging means into engagement with the carriage, means whereby the lateral motion of said actuating member is transmitted to the intermediate member, an 65 arm projecting from said intermediate member, and a retaining member carried by the base portion and adapted to engage said arm to prevent lateral movement of said 70 rocking member until the said member has been oscillated sufficiently to bring the carriage-engaging means into engagement with said carriage.
15. In a calculating machine, the combination with a supporting structure, of a carriage mounted and movable thereon, a shaft mounted in said structure, an element 75 pivotally mounted upon and movable longitudinally of said shaft, and a member operatively associated with the element and having a definite limited movement whereby the said element is first oscillated upon the shaft to bring it into engagement with the carriage and is thereafter shifted longitudinally of the shaft to shift the carriage to a new position upon the said structure. 80
16. In a calculating machine, the combination with a supporting structure, of a carriage mounted and movable thereon, a shaft mounted in said structure, an element 85 pivotally mounted upon and movable longitudinally of said shaft, and a reciprocatory member operatively associated with the element and adapted on each reciprocation to oscillate the element to bring it into engagement with the carriage and to shift the element longitudinally of the shaft thereby to shift the carriage to a new position on the supporting structure. 90
17. In a calculating machine the combination with a base structure, of a carriage 95 movably mounted in the base, and manually operated mechanism for shifting the carriage on the base, including an actuating member independent of the carriage and adapted to actuate said mechanism to shift the carriage in both directions. 100
18. In a calculating machine the combination with a base structure, of a carriage 105 movably mounted in the base, and manually operated mechanism for shifting the carriage on the base, including an actuating member mounted on the base and adapted to actuate said mechanism to shift the carriage in both directions. 110
19. In a calculating machine the combination with a base structure, of a carriage 115 movably mounted and having a plurality of locked positions on the base, a locking member carried by the carriage and adapted to engage the base to maintain the carriage in the respective locked positions, and manually operated mechanism independent of the carriage for disengaging the locking member and for shifting the carriage from one 120 position to another including an actuating element adapted to actuate said mechanism to shift the carriage in both directions. 125
20. In a calculating machine the combina-

tion with a base structure, of a carriage movably mounted and having a plurality of locked positions on the base, a locking member on the carriage adapted to engage the base in maintaining the carriage in the respective locked positions, and manually operated mechanism independent of the car-

riage adapted to disengage the locking member and to shift the carriage on the base and including an actuating member having limited movement in the base whereby the carriage may be shifted accurately from one locked position to the next in both directions.

10 OTTO P. SCHUMAN.
